UNITED STATES PATENT OFFICE

1,998,322

HIGH FREQUENCY CIRCUIT

Ira J. Kaar, Schenectady, N. Y., assignor to General Electric Company, a corporation of New York

Application April 29, 1933, Serial No. 668,602

4 Claims. (Cl. 250—17)

My invention relates to high frequency circuits and more particularly to coupling circuits, or networks, for use between a high frequency source and a load.

5 In high frequency transmitting systems it frequently happens that it is desirable to supply any desired frequency within a wide range of frequencies from a transmitter to a single antenna, or to supply a single frequency from a 10 transmitter to antennae of widely different lengths and, of course, of widely different impedance characteristics. At the same time it is necessary for efficient operation of the system that the circuits be so constructed and arranged 15 that the transmitter works into a load of pure resistance of a certain optimum value dependent upon the characteristics of the discharge device employed and irrespective of the impedance of the antenna at the particular frequency at which the 20 system operates.

One of the objects of my invention is to provide improved means whereby this result is effected.

A further object of my invention is to provide 25 means whereby a particular transmitter may be caused efficiently to supply oscillations to antennae of somewhat greater range of lengths than has heretofore been possible.

The novel features which I believe to be characteristic of my invention are set forth with 30 particularity in the appended claims. My invention itself, however, both as to its organization and method of operation, together with further objects and advantages thereof may best be understood by 35 reference to the following description taken in connection with the accompanying drawing in which I have shown in Figs. 1, 6, and 7 certain embodiments of my invention; in Figs. 2 and 5 certain characteristics relating to its operation; 40 and in Figs. 3 and 4 certain details.

Referring to Fig. 1 of the drawing I have conventionally indicated therein an electron discharge device 1 which may for example comprise the last stage of a high frequency transmitter. This transmitter has a tuned output circuit 2 comprising an inductance 3 and a pair of condensers 4. The upper terminal of the oscillatory circuit is connected to the anode of the discharge device and the lower terminal is connected to the cathode of the discharge device through a condenser 5 having capacitance equal to the internal capacitance between the anode and cathode of the discharge device. As thus arranged the opposite sides of the oscillatory 55 circuit 2 are capacitively balanced with respect

to ground and the discharge device 1 is thereby adapted to operate into a balanced load circuit, such for example as an antenna of the doublet type, or into a balanced transmission line. It will be understood, however, that this type of transmitter circuit is described simply by way of illustration and that my invention is in no wise limited to systems adapted only for operation into balanced loads.

The impedance characteristics of the load circuit into which the transmitter operates may of course vary widely both in reactance and in resistance, whereas it is necessary to efficient operation of the discharge device 1 that it operate into a pure resistance load having a certain optimum value dependent upon the characteristics of the electron discharge device employed. To effect this result inductances 6, tuning inductances 7, and tuning condensers 8 are provided in each side of the output circuit together with a portion of artificial line 9 which I shall hereinafter describe, and switching devices 10 and 11. The purpose of the inductance 7 and condenser 8 is primarily to provide means whereby the reactance of the load circuit may be neutralized. The inductance 6 is of such a value that in combination with the other elements of the system it causes the pure resistance of the load circuit when tuned by elements 7 and 8 to be translated into a value suited for best operation of the discharge device.

To explain more fully the operation of the system shown in Fig. 1 reference may be made to Fig. 2 showing the impedance characteristics of antennae in general. The curve A of this figure shows the variations in the reactance of a vertical antenna with frequency. It will be observed that at low frequencies the reactance of the antenna is relatively large, but that it progressively decreases to zero at a point c corresponding to the natural frequency of the antenna. It then becomes positive and progressively increases to an extremely high value after which it suddenly drops through zero to an extremely high negative value, after which it again progressively diminishes. This cycle repeats itself successively at the higher frequencies.

The curve B represents the relation between the resistance of the antenna and the frequency. It will be observed that the resistance has maximum values at frequencies approximately midway between points of the curve A corresponding to maximum positive and negative reactance, or where the reactance more abruptly changes sign.

It will be seen from these curves that both the reactance of the antenna and the resistance vary over an extreme range at different frequencies and that if the tube 1 is to operate into a pure 5 resistance load of optimum value it is necessary that the reactance of the antenna, or load circuit, be neutralized at the operating frequency and that its resistance be translated to the optimum value determined by the characteristics 10 of the discharge device.

The inductance 7 and condenser 8 are provided primarily to tune out the reactance of the antenna and the reactance 6 is provided primarily to provide the proper translation in the resistance 15 of the load although in the final adjustment of the system, as will presently be seen, these functions are shared by both of these elements as well as by the oscillatory circuit 2.

When the switch 10 is in the lower position it 20 will be observed that the inductance 7 on each side of the circuit is in series with the antenna and the condenser 8 is connected between the antenna and ground. The position of these two 25 elements in the circuit is reversed when the switch 10 is in its upper position. By varying these two elements of the circuit the reactance of the antenna may be entirely balanced out over a certain range of frequencies.

The inductance 6 may be considered as one 30 element of a network such as that shown in Fig. 3 in which is shown an inductance X_2 connected in series with the line and a condenser X_1 connected in shunt with the line on the input side of the inductance X_2 . It can readily be shown 35 that if such a network be connected between a source having a resistance R_0 and a load R and that if the values X_2 and X_1 be adjusted as follows

$$40 \quad X_1 = R_0 \sqrt{\frac{R}{R_0 - R}}$$

and

$$X_2 = \sqrt{R(R_0 - R)}$$

then the impedance looking into the network 45 X_1, X_2 is equal to R_0 . That is, the source works into a resistance equal to its own resistance. I employ such a network in Fig. 1 although it will be noticed that since X_1 is in parallel with the circuit it is in parallel with the condensers 4. 50 The capacitance of this condenser X_1 is therefore incorporated into the condensers 4. This means that the oscillatory circuit 2 is not, in itself, tuned to the frequency at which the system operates, but instead is tuned to that frequency only when considered in combination 55 with the inductance 6 and the load, including the tuning means. The oscillatory circuit, of itself, is actually tuned to a frequency different from the frequency at which the system operates, the capacitance 4 being increased by an amount equal to the required capacity X_1 . The load circuit then presents a unity power factor load to the tube.

The impedance matching network may if desired be of the form shown in Fig. 4 in which the series element X_2 is a capacitance and the shunt element X_1 is an inductance. In this case the inductance 3 may be so constructed as to render the additional element X_1 unnecessary, i.e., its inductance may be reduced by an amount equivalent to the addition of the inductance of element X_1 . It is found, however, in practical application of the system that the form shown in Fig. 3 is preferable owing to its inherent 70 property of suppressing harmonic frequencies due

both to its series inductance and shunt capacitance.

The impedance matching network shown in both Figs. 3 and 4 are of the step-down type, the step-down being in the direction of the arrows, that is, the input resistance R_0 is greater than the resistance R . If it happens, in a particular application, that the resistance of the antenna be greater than the optimum resistance into which the tube should operate, then these networks may be reversed in the circuit, or in other words, may be modified by connecting the reactance X_1 across the circuit at the opposite end of the reactance X_2 . In this latter case the reactance X_1 may be provided in the case of Fig. 3 15 by so tuning the antenna that it is capacitive to an extent sufficient to effect the desired impedance match, or in the case of Fig. 4, by so tuning the antenna that it is inductive by an amount sufficient to effect the impedance match. 20

In the methods above described the shunt element of the impedance matching network is either incorporated into the tuned circuit 2 or into the antenna tuning element as the case may require. These methods are satisfactory for 25 operation over a wide range of frequencies on either side of the different points C of the curve A of Fig. 2. At frequencies beyond these ranges, however, a different adjustment of the apparatus may be necessary in order to permit the use of 30 the same equipment at these frequencies. Such an adjustment may be necessary, for example, in case where a condenser, or inductance, which is adapted for tuning of the antenna to a frequency near one of the points C of the curve A of Fig. 2 35 may be unadapted for tuning to a frequency widely different from a frequency corresponding to these points of the curve or vice versa. In such a case it may be impossible entirely to tune out the reactance of the antenna by means of the 40 antenna tuning elements 7, 8. Accordingly an impedance having both resistance and reactive components are presented to the output of the impedance matching network. The impedance looking into the input side of the impedance 45 matching network will then, likewise, have both resistance and reactive components. It has been found, however, that by proper adjustment of the series element 6 and by tuning the circuit 2 to a frequency slightly different from the frequency 50 at which the system operates by an amount sufficient to neutralize the reactance of the impedance looking into the matching network, the desired unity power factor load of optimum value may be presented to the tube. This may be accomplished even though neither the circuit 2 nor the antenna are tuned per se, to the operating frequency. In this case all of the elements of the system described cooperate to present a unity power factor load of optimum value to the tube. 60

By so adjusting the system the frequency range over which the same equipment may be employed is considerably extended. In certain extremely narrow ranges of frequency, however, as for example in a range of frequencies of approximately 65 100 cycles where the reactance is extremely high, it is desirable that certain additional means be provided to accomplish the required tuning and impedance match. This means comprises in accordance with my invention, the additional line 70 9 which when included in the circuit actually changes the length of the antenna. This element of the system may comprise a conductor arranged in zigzag form on a non-conducting board in the transmitter housing, for example, 75

so as to have a minimum of concentrated capacitance and inductance and to have distributed capacitance to ground and distributed inductance substantially equal to that of an equivalent length 5 of the actual antenna itself. Thus by opening the switches 11 and thereby including such a unit in circuit with the antenna the actual length of the antenna is changed to one at which tuning may be more readily effected. This is illustrated 10 in Fig. 5 in which the curve D may be considered as the reactance curve of the antenna employed. If it were desired to tune the antenna sharply at a frequency closely approximating one of the frequencies at which the antenna has maximum 15 reactance difficulty might be encountered. This difficulty, however, may be obviated by opening the switch 11 and thereby changing the antenna to one having an impedance characteristic as indicated by the curve E of Fig. 5. The frequencies referred to then, respectively, fall upon the curve 20 E at the points F such that the impedance is one whereby tuning may be readily effected.

The condensers 12 shown in Fig. 1 are blocking condensers to prevent the direct current electro-motive force which is supplied to the anode of the discharge device from being impressed upon the remainder of the system.

A switch 13 is provided for the purpose of disconnecting one side of the line in cases where 30 the transmitter is to be utilized to supply an antenna of the vertical type, for example, or a transmission line one side of which is grounded.

Fig. 6 shows an embodiment of my invention similar to Fig. 1 except that the switches 10 and 35 11 are removed. It is found in most practical cases that these elements are unnecessary. The tuning device comprises the series inductance 7 and shunt capacitance 8. This arrangement of the tuning elements is preferred since it has the 40 effect of reducing harmonics. A switch 14 is provided to connect the system to a vertical antenna which is indicated at 15 and to disconnect it from a transmission line which may extend from the terminals 16. When the switch 14 is in its upper position the additional switch 17 is moved to its right-hand position thereby short 45 circuiting the impedance elements 6, 7, and 12 in the lower portion of the network. When the switch 14 is in its lower position the switch 17 50 may be moved to the left for operation as described in connection with Fig. 1.

The arrangement shown in Fig. 7 differs from that shown in Figs. 1 and 6 in that the transmitter is indicated as one of the push pull type 55 adapted for operation into a balanced transmission line or antenna of the doublet type. The system 18 comprises the tuning network and cooperates with the impedance matching element 6 and oscillator circuit 2 in the same manner as has been described in connection with Fig. 1.

While I have shown particular embodiments of my invention it will be understood that I do not wish to be limited thereto since many modifications may be made both in the circuit arrange-

ment and instrumentalities employed and I contemplate by the appended claims to cover any such modifications as fall within the true spirit and scope of my invention.

What I claim as new and desire to secure by Letters Patent in the United States is:

1. In combination, an electron discharge device having an oscillatory output circuit, a load connected thereto having reactance, tuning elements for both said oscillatory output circuit and said load, the reactance of said load being such that said tuning element for said load is incapable of tuning said load to resonance at the frequency supplied by said electron discharge device, a reactive element between said output circuit and load, the tuning element for said oscillatory output circuit being so adjusted relative to the reactance of said element that said oscillatory output circuit is sufficiently detuned from the frequency at which said discharge device operates to cause said discharge device to operate into a load of pure resistance and of optimum value.

2. In combination, an electron discharge device having an oscillatory output circuit, an antenna connected thereto, means to neutralize the reactance of said antenna at frequencies at which the reactance has a certain value, said means being incapable of completely neutralizing said reactance at frequencies at which said reactance has a widely different value, and a reactive element between said output circuit and antenna, the reactance of said element, and the reactance of said output circuit being so proportioned with respect to each other that said electron discharge device operates into a load of pure resistance of optimum value at the frequencies at which the reactance of said antenna is not completely neutralized by said means.

3. In combination, an electron discharge device, arranged for operation at a certain frequency, an oscillatory output circuit therefor, an antenna circuit, and a reactive element connected between said oscillatory output circuit and said antenna circuit, one of said circuits being tuned to resonance at a frequency different from the frequency at which said electron discharge device operates and so related to the reactance of said element that said discharge device operates into a load of pure resistance and of optimum value.

4. In combination, an antenna, means to supply high frequency oscillations thereto, said antenna having such extremely high reactance at the frequency supplied by said means as to render impractical the tuning of said antenna by concentrated reactance, and means to reduce said reactance, said means comprising a non-radiating conductor connected in series with said antenna, said conductor having distributed inductance and capacity approximately equal to that of an equal length of said antenna, and having length such that the combined reactance of said antenna and conductor is substantially lower than that of said antenna.

IRA J. KAAR.
